UNITED STATES PATENT OFFICE.

CHARLES JOSEPH RHODES AND THOMAS HENRY WEBB, OF WAKEFIELD, ENGLAND.

PRESS FOR OPERATING UPON METAL AND OTHER SHEETS.

1,416,873.

Specification of Letters Patent. Patented May 23, 1922.

Application filed June 21, 1919. Serial No. 305,280.

To all whom it may concern:

Be it known that we, CHARLES JOSEPH RHODES, chairman of directors, and THOMAS HENRY WEBB, general manager, both subjects of the Kingdom of Great Britain, residing at Grove Iron Works, Wakefield, England, have invented certain new and useful Improvements in or Relating to Presses for Operating upon Metal and Other Sheets, 10 of which the following is a specification.

This invention comprises certain improvements in or relating to presses for operating upon metal and other sheets, and refers particularly to the mechanism for feeding 15 the sheet.

In this type of mechanism, provision has been incorporated for advancing the sheet in two directions. Advantageously the sheet is advanced backwardly and forwardly 20 in lateral directions, and is advanced in a vertical direction or a direction transversely to these lateral directions, at the end of each traverse. In a press for severing a series of sheet metal or other blanks from a sheet, 25 these blanks may be successively cut after each of a series of intermittent lateral movements of the sheet, and the arrangement may be such that in each traverse the positions at which the metal is stamped or cut 30 are staggered in relation to the positions at which the metal is stamped in the preceding traverse. In the case of circular stampings, the blanks are thereby cut with the waste of a minimum amount of sheet metal.

The present invention has for its purpose 35 to provide for the accurate location of the sheet prior to each stamping or pressing operation. In cases in which a series of blanks are desired having special markings 40 thereon, it is the practice to apply these markings to the sheet before subjecting it to the stamping process. To stamp the blanks from the sheet so that the markings shall be appropriately positioned upon the 45 blank necessitates the accurate locating of the blank in a predetermined position prior to each stamping operation; it is to this process of accurate location that the present invention is particularly directed.

The type of this class of mechanism to 50 which this invention particularly relates is that in which a carrier member is provided adapted for the attachment thereto of the sheet or the equivalent, said carrier member 55 being adapted to be intermittently advanced or displaced by a pawl, and in which pro-

vision which is mechanically actuated positively (as distinguished from spring actuated automatically) is incorporated in addition to the feeding means, for locating the sheet after each feeding operation. According to the present invention, in this type of mechanism, in the locating action the carrier member is adapted to be engaged by a part which in the act of engaging moves in a direction essentially transversely to that of the movement of said carrier member. The said part advantageously takes the form of a slide working in a guide which is immovable longitudinally of the direction of movement of the carrier member, said slide having a V-shaped or equivalent extremity adapted to engage within V-shaped or equivalent notches in the carrier member.

A brake is also provided in connection with the carriage; this brake is adapted to be automatically disengaged during the engagement of the indexing device.

In order that this invention may be clearly understood and readily carried into practice, reference may be had to the appended explanatory drawings, upon which:

Figure 1 is a plan view of a mechanism according to the present invention.

Figure 2 is a sectional end elevation of the mechanism shown in Figure 1.

Figure 3 is a face view of the gripper member and its supporting frame herein-after referred to.

In a convenient embodiment of the present invention, the carriage *e* is provided with a bar *a* of metal having at intervals along its length V-shaped notches *b*. At right angles to this bar a bolt *c* is adapted to slide having a V-shaped extremity adapted to engage within any one of the said notches. Below the notched bar a brake *d* is provided and adapted to engage with the carriage or a part provided thereon. This brake is also adapted to move towards and away from the carriage in parallelism with the locating bolt *c*.

The locating bolt *c* and brake *d* are each adapted to be actuated respectively by cams *e*, *f*, sliding in directions parallel with the direction of movement of the carriage. These sliding cams are collectively reciprocated by any suitable mechanism. Through a rod *g*, a shaft *h* is appropriately oscillated, which shaft is furnished with a lever arm *i* by which a longitudinal reciprocatory movement is imparted to the longitudinally slid-

ing cams *e*, *f* through the medium of a link *j*. The cam surfaces of these cams are so located, and the cams are adapted to be so actuated, that after the carriage has been dis-
5 placed or fed by the pawl *x* which is adapted by appropriate means to intermittently ad-
vance the carriage, the brake is disengaged and the locating bolt is then advanced by its cam into the notch in the bar with which it
10 cooperates, to thereby precisely position the carriage prior to the stamping operation.

The cam *e'* for operating the locating bolt is supported at the rear by two L-shaped blocks *k* which are in turn controlled by
15 powerful springs *l*. These blocks function as resistance pieces by virtue of which the cam is adapted to displace the locating bolt. If by any reason it should happen that the carriage is advanced in an excessive degree
20 so that the notch in the bar thereon is completely beyond the nose of the locating bolt, the cam for actuating the locating bolt is still enabled to reciprocate longitudinally by virtue of the spring-mounted blocks in relation to which it operates.
25

A spring *m* is suitably incorporated in the locating bolt to withdraw it at the appropriate time, *n* is a spring for operating the brake *d*.

30 The carriage *e* is adapted to carry a frame *o* which supports a gripper member *p* adapted to be engaged with the upper edge of the plate. For this purpose the frame *o* may be rigidly provided with a bracket *o'* which
35 may be secured in any appropriate manner to the carriage *e*. This gripper member is adapted intermittently to descend by gravity, being automatically released after each lateral feed traverse and retained by a sub-
40 sequent stop *q'*. These stops are located upon a vertical member *q* adapted to be automatically oscillated and according to the present invention the said vertical member is located centrally or substantially centrally
45 in the width of the gripper *p* for the sheet metal. Said gripper is thus effectively balanced in relation to the vertical feeding means therefor; it is not liable as a result of wear to change its position in such manner
50 as would detract from the accurate location of the sheet during the stamping operations. Conveniently the frame by which the gripper is carried comprises two vertical paral-

lel rails or runways, with each of which two spaced rollers *r* carried by the gripper co-
55 operate; the four rollers carried by the gripper are located in the positions of the corners of a rectangle or square, and the gripper is thus maintained in a position whereby it feeds the sheet in a precisely vertical line. By "vertical" is meant vertical as viewed from the aspect of elevation facing the surface of the sheet. Advantageously the sheet is inclined as viewed from its edge during
60 the stamping operations.
65

What we claim as our invention and desire to secure by Letters Patent is:—

1. Sheet feeding mechanism for power presses and the like, including a carrier member mounted for movement in a right line 70 and having spaced notches, a guide immovable longitudinally of the direction of movement of the carrier member, and a locating slide, arranged for movement in said guide and having means to engage the notches of 75 said carrier member.

2. Sheet feeding mechanism for power presses and the like, including a carrier member mounted for movement in a right line 80 and having spaced notches, a guide immovable longitudinally of the direction of movement of the carrier member, a locating slide, arranged for movement in said guide and having means to engage the notches of said 85 carrier member, a cam to operate said slide, and a resilient yieldable means to actuate said cam.

3. Sheet feeding mechanism for power presses and the like, including a carrier member mounted for movement in a right line 90 and having spaced notches, a guide immovable longitudinally of the direction of movement of the carrier member, a locating slide, arranged for movement in said guide and having means to engage the notches of said 95 carrier member, a brake for the carriage, and releasing means for the brake operable during the locating operation.

In witness whereof we have hereunto set our hands in the presence of two witnesses. 100

CHARLES JOSEPH RHODES.
THOMAS HENRY WEBB.
